DESIGN FOR A COMBINED HINGED NUT AND BEARING PLATE

Guy P. Wherren, Glendale, Calif.

Application July 28, 1937, Serial No. 70,708

Term of patent 7 years

To all whom it may concern:

Be it known that I, Guy P. Wherren, a citizen of the United States, residing at Glendale, in the county of Los Angeles and State of California, have invented a new, original, and ornamental Design for a Combined Hinged Nut and Bearing Plate, of which the following is a specification, reference being had to the accompanying drawing forming a part thereof.

Fig. 1 is a perspective view of a combined hinged nut and bearing plate embodying my design;

Fig. 2 is a side elevation of the same.

I claim:

The ornamental design for a combined hinged nut and bearing plate, as shown.

GUY P. WHERREN.
